PROCESS OF CLEANING SCREENS.

1,367,111.

Specification of Letters Patent.

Patented Feb. 1, 1921.

Application filed May 31, 1917. Serial No. 171,999.

To all whom it may concern:

Be it known that I, RICHARD G. WOODBRIDGE, Jr., of Wilmington, in the county of New Castle and in the State of Delaware, 5 have invented a certain new and useful Improvement in Processes of Cleaning Screens, and do hereby declare that the following is a full, clear, and exact description thereof.

My invention relates particularly to a 10 process of cleaning screens used in the manufacture of nitrocellulose or nitrocellulose compositions, although it is applicable to other purposes.

The object of my invention is to provide 15 a process for cleaning screens as, for example, screens made of wire mesh or perforated plates, so as to remove the colloided or uncolloided nitrocellulose therefrom which has accumulated in the screening process in the manufacture of nitrocellulose or nitrocellulose compositions. In the process of making nitrocellulose or nitrocellulose compositions, the nitrocellulose, or composition containing the same, is 20 passed through one or more screens which may be of woven wire or perforated metal, or both, and the material of which they are made may be steel, iron, brass or copper, the purpose being to remove all foreign materials such as wood, fibers, hair, sand, metallic particles, etc. From time to time it 25 therefore becomes necessary to clean these screens in order to remove the accumulated foreign materials and adhering nitrocellulose or nitrocellulose composition. The usual 30 method to clean these screens has been to set fire to the nitrocellulose or nitrocellulose composition. This burning process makes the metal brittle and in consequence the 35 screens can only be used a relatively few times before discarding, as each burning treatment tends to make the screens more brittle. Another method of removing nitrocellulose or nitrocellulose compositions from 40 screens is to soak the screens in solvent, such as acetone or a mixture of ether and ethyl alcohol. This is not a very satisfactory method as the operation is slow, and the 45 complete removal of the nitrocellulose or nitrocellulose composition is only affected by repeated treatment with fresh solvent. The decomposing action by the use of an 50 alkaline solution is very violent, and not without danger where relatively large

amounts of nitrocellulose and nitrocellulose 55 compositions, as in this case, are decomposed. However, I have discovered that there is little or no danger in the operation, provided the process is carried out as hereinafter described and, furthermore, that the 60 tensile strength of the metal composing the screen is practically uninjured by my process, thereby making it possible to use the screens many more times before discarding, than has heretofore been possible. It is the 65 object of my invention to remove these adhering materials from the screens in such a manner as to avoid damage to the screens as far as possible. A further object of my invention is to remove such adhering materials 70 from the screens by applying thereto a salt solution having an alkaline reaction, and which is of such a nature that it effectively removes the nitrocellulose or composition containing the same, and thus removes 75 the bulk of the foreign materials and loosens the remaining foreign materials in the meshes of the screens and without attacking, to any detrimental extent, the screens themselves. An object of my invention is thus 80 to make use of solutions of alkali hydroxids, sulfids or carbonates, or hydroxids or sulfids of the alkali earth metals. A further object is to remove the remaining foreign particles after such treatment, by the use of a rotating 85 brush. A further object is to restore the screens to their original shape as by rolling the same. Another object is to carry out my process without subjecting the screens to such a high temperature as would 90 result in damage thereto. Further objects of my invention will appear from the detailed description thereof contained hereinafter, it being important that the cleaning shall be executed at a temperature and at 95 a concentration high enough to attack and remove the nitrocellulose or nitrocellulose composition without causing any appreciable attack upon the metal of the screen.

While my invention is capable of embodiment in many different forms, for the purpose of illustration I shall describe only certain forms of my invention hereinafter, and I have shown only one form of apparatus which may be used in connection with my 105 invention in the accompanying drawing, in which—

The figure is a vertical section of an appa-

ratus which may be used in connection with my invention.

In the drawing I have shown an iron or steel tank 1, provided with a false bottom or iron grating 2, near the bottom thereof, said tank being provided with a valved inlet 3 for water and a valved inlet 4 for steam at the bottom thereof. In the interior of the tank 1 there are shown a plurality of baskets 5 having handles 6, said baskets 5 being made of expanded metal and being preferably provided to receive a plurality of screens 7 to be cleaned in accordance with my invention. The tank 1 has a valved draw-off pipe 8 at the bottom thereof.

In carrying out my invention, after the baskets 5 with the screens 7 therein which have been used in the screening operation in the production of nitrocellulose or nitrocellulose compositions, have been placed in the tank 1, said tank is partially filled with caustic soda solution containing from 25% to 30% of sodium hydroxid by weight, dissolved in water. Any desired grade of caustic soda may be used. The caustic soda solution is then heated by the introduction of steam from the pipe 4 until the solution has a temperature of preferably from 70° to 80° C. The caustic soda thereupon attacks the colloided and uncolloided nitrocellulose vigorously, thus decomposing and entirely removing the same from the screens in from thirty minutes to two hours, depending upon the thickness of the accumulated nitrocellulose or nitrocellulose composition, also upon the percentage of solvents contained in the nitrocellulose composition, and upon the temperature of the caustic soda solution, also upon the strength of the caustic soda solution. The strength of the caustic soda solution may be above 30%, but a 30% solution enables the removal of the materials from the screens to be carried out with sufficient rapidity. The solution of caustic soda may be used and reused until the strength is reduced to from 3% to 4% sodium hydroxid by weight, whereupon the solution may be either strengthened up to 30% by the addition of fresh caustic soda, or discarded altogether. The caustic soda solution will in this way remove very nearly all of the foreign materials on the screens and, in addition, the nitrocellulose or nitrocellulose composition adhering to the screens. The baskets 5 are then ordinarily removed from the solution and subjected to washing with water and drying in a current of hot air. Any of the foreign materials such as wood, fibers, hair, sand, metallic particles, etc., which remain entangled in the meshes of the screens, and which are left therein after the greater amount of the same have been removed in the preceding steps of the process, are loosely held in the meshes 65 or perforations of the screens and can

readily be removed therefrom by brushing as, for example, with a rotary brush. The screens can then be straightened in any suitable manner as, for example, by passing through a pair of rolls. The process as just described is particularly applicable to screens made of steel or iron, inasmuch as the caustic soda solution has no appreciable action thereon. However, the process is also applicable to copper, brass and phosphor bronze screens, in which case I prefer to use a caustic soda solution initially weaker than 30% by weight, but I do not limit myself to any particular strength, it being obvious that I would use that strength of solution particularly adapted for removing the nitrocellulose or nitrocellulose composition with the minimum detrimental action on the screens, and that I would remove the screens from the solution before it had time to react upon the metal of the screen to a detrimental extent. Furthermore, it will be understood that a number of different decomposing agents may be used instead of the caustic soda as, for example, caustic potash, alkali sulfids, alkali carbonates and hydroxids and sulfids of the alkali earth metals, or mixtures of the same. Screens which have been cleaned in this manner may be used a great many times by being repeatedly cleaned.

While I have described my invention above in detail, I wish it to be understood that many changes may be made therein without departing from the spirit of the same.

I claim:

1. The process of cleaning without appreciably attacking metallic screens through which nitrocellulose compositions have been passed, which comprises decomposing the nitrocellulose adhering to the screen through the application of a salt solution having an alkaline reaction while controlling the intensity of the reaction by regulating the temperature and the concentration.

2. The process of cleaning without appreciably attacking metallic screens through which nitrocellulose compositions have been passed, which comprises decomposing the nitrocellulose adhering to the screen through the application of a caustic soda solution while controlling the intensity of the reaction by regulating the temperature and the concentration.

3. The process of cleaning without appreciably attacking metallic screens through which nitrocellulose compositions have been passed, which comprises decomposing the nitrocellulose adhering to the screen through the application of a caustic soda solution at a temperature approximately between 70° and 80° C.

4. The process of cleaning without appreciably attacking metallic screens through

120

- which nitrocellulose compositions have been passed, which comprises decomposing the nitrocellulose adhering to the screen by immersing the screen in a salt solution having an alkaline reaction while controlling the intensity of the reaction by regulating the temperature and the concentration.
5. The process of cleaning without appreciably attacking metallic screens through which nitrocellulose compositions have been passed, which comprises decomposing the nitrocellulose adhering to the screen by immersing the screen in a caustic soda solution while controlling the intensity of the reaction by regulating the temperature and the concentration.
10. The process of cleaning without appreciably attacking metallic screens through which nitrocellulose compositions have been passed, which comprises decomposing the nitrocellulose adhering to the screen by immersing the screen in a caustic soda solution while controlling the intensity of the reaction by regulating the temperature and the concentration.
15. The process of cleaning without appreciably attacking metallic screens through which nitrocellulose compositions have been passed, which comprises decomposing the nitrocellulose adhering to the screen by im-

mersing the screen in a caustic soda solution at a temperature in the neighborhood of 80° C.

7. The process of cleaning without appreciably attacking metallic screens through which nitrocellulose compositions have been passed, which comprises decomposing the nitrocellulose adhering to the screen through the application at a temperature high enough to attack the nitrocellulose without appreciably attacking the metal of a salt solution having an alkaline reaction, washing the screen, and brushing the residue therefrom.

20. In testimony that I claim the foregoing I have hereunto set my hand.
